CLAIM

I claim the ornamental design for the decorative television bezel, as shown and described.

DESCRIPTION

FIG. 1 is a front view of the decorative television bezel.

FIG. 2 is a rear view of the claimed design.

FIG. 3 is a side view of the claimed design.

FIG. 4 is a top view of the claimed design; and,

FIG. 5 is a perspective view of the claimed design.

The broken lines of FIG. 5 represent a television, which is environmental matter that is not part of the claimed design.
